US0D1052992S

(12) **United States Design Patent** (10) Patent No.: **US D1,052,992 S**
(45) Date of Patent: ** Dec. 3, 2024

(54) **BIOMETRIC HITCH LOCK**

(71) Applicant: **bROK Products, LLC**, Akron, OH (US)

(72) Inventors: **Francis Bernart**, Akron, OH (US); **Xuehua Wan**, Hangzhou (CN); **Wenteng Zhou**, Hangzhou (CN)

(73) Assignee: **bROK Products, LLC**, Akron, OH (US)

(**) Term: **15 Years**

(21) Appl. No.: **29/819,647**

(22) Filed: **Dec. 16, 2021**

(51) LOC (14) Cl. **08-07**

(52) U.S. Cl.

USPC **D8/330**

(58) **Field of Classification Search**

USPC D8/330, 331, 339, 341; D12/162

CPC B60D 1/025; B60D 1/60; B60D 1/52

See application file for complete search history.
